UNITED STATES PATENT OFFICE

DAVIS M. GIBBONS, OF KERSHAW, SOUTH CAROLINA

CASKET-HANDLING DEVICE

Application filed June 11, 1929. Serial No. 370,044.

My invention relates to improvements in casket handling apparatus.

In accordance with my invention, a track is provided formed in two sections, which are detachably connected, and each section is adapted to be folded or collapsed. A carriage is provided to travel upon the track sections and this carriage is collapsible and is also longitudinally adjustable. The several parts of the apparatus being thus collapsible render it possible for the same to be conveniently transported in a wagon or the like, and to be quickly and conveniently extended for use.

15 In the accompanying drawings, forming a part of this specification, and in which like numerals are employed to designate like parts throughout the same,

Figure 1 is a plan view of apparatus embodying my invention,

Figure 2 is a side elevation of the same,

Figure 3 is a perspective view of the carriage,

Figure 4 is a transverse section taken on line 4—4 of Figure 2,

Figure 5 is an end elevation of the carriage collapsed,

Figure 6 is a perspective view of the track sections assembled,

30 Figure 7 is a transverse section taken on line 7—7 of Figure 6.

Figure 8 is a detailed longitudinal section through the connected ends of the track sections, on line 8—8 of Figure 7,

35 Figure 9 is an end elevation of one track section collapsed, and,

Figure 10 is a horizontal section taken on line 10—10 of Figure 6.

In the drawings, wherein for the purpose 40 of illustration is shown a preferred embodiment of my invention, the numeral 10 designates track sections, which are identical. Each track section embodies longitudinal spaced bars 11, rigidly connected at their ends with supporting members or blocks 12. The blocks 12 in each track section are rigidly connected with transverse horizontal bars 13 which have hinged knee joints 14, such knee joints breaking upwardly, and 45 positively preventing the bars 13 from being

swung downwardly below the horizontal. The longitudinal bars 13 carry rails 15, rigidly attached thereto, and these rails have their outer edges beveled, as shown at 16, while their inner edges are vertical. It is thus seen that each track section may be folded transversely upon itself, to assume the collapsed position, shown in Figure 9.

The supporting members or blocks 12 at the adjacent ends of the track sections 10 are detachably connected, and for this purpose, the supporting members 12 of one track section are equipped with tongues 17, to enter recesses 18 formed in the adjacent blocks of the other track section, and such adjacent blocks are provided with transverse openings for receiving pins 19, passing through apertures 20 in the tongues 17. When the adjacent blocks 12 are thus securely detachably connected, the rails 15 of the track sections are in alignment. The inner blocks 12 are shorter than the outer blocks 12, and the rails 15 pass over the tops of the inner blocks, while the outer blocks project above the rails 15 and serve as stops, 75 for the wheels of the carriage, to be described.

The carriage embodies a rectangular frame 21, see more particularly Figure 3, and this frame embodies longitudinal bars, 80 including outer and inner telescoping tubes 22 and 23. The tubes 23 are longitudinally adjustable within the tubes 22, and are clamped therein by bolts 24 or the like. The tubes 22 and 23 are rigidly connected with 85 supporting members or blocks 24, and these blocks are also rigidly connected with transverse bars 25. At their inner ends, these transverse bars have hinged knee joint connections 26 which break upwardly, but positively limit the downward movement of the bars 25, below the horizontal. The supporting members or blocks 24 have their lower ends forked, for receiving flanged 90 wheels 27, adapted to travel upon the rails 15. The blocks 24 extend above the sides and ends of the carriage, to properly support the casket lowering device so that the rotatable cylinders of the same will be free 95 to turn, in lowering the casket.

The operation of the apparatus is as follows:

The track sections 10 are distended and their adjacent ends connected by means of the tongues 17 and pins 19, and one track section is placed over the grave. The carriage is first longitudinally adjusted, depending upon the length of the casket, and may then be arranged upon the track section remote from the grave. The casket lowering device is mounted upon the carriage, and the casket is supported upon the carriage through the medium of the casket lowering device. When desired, the carriage with the casket thereon, is shifted longitudinally to the track section over the grave, and the casket lowered. The carriage may be readily returned upon the track section remote from the grave. The carriage track sections may now be removed from the proximity to the grave, whereby the grave may be filled as is well known. The track section arranged over the grave, and the carriage arranged thereon, being open frames the casket may be lowered down through the same, into the grave.

It is to be understood that the form of my invention, herewith shown and described, is to be taken as a preferred example of the same, and that various changes in the shape, size and arrangement of parts, may be resorted to without departing from the spirit of my invention, or the scope of the subjoined claim.

Having thus described my invention, I claim:—

A carriage for supporting a casket lowering device, comprising an open rectangular frame including sides and collapsible hinged ends, and vertical blocks connecting the sides and ends, said blocks serving to support the corner members of a casket lowering device so that the casket may pass downwardly through the frame, and wheels supporting the blocks.

In testimony whereof I affix my signature.
DAVIS M. GIBBONS.
